UNITED STATES PATENT OFFICE.

ARTHUR J. LA FAY, OF TORONTO, ONTARIO, CANADA, ASSIGNOR OF ONE-HALF TO
HUGH R. TUDHOPE, OF ORILLIA, ONTARIO, CANADA.

HEATING APPARATUS.

1,391,838.

Specification of Letters Patent. Patented Sept. 27, 1921.

Application filed March 25, 1919. Serial No. 284,962.

To all whom it may concern:

Be it known that I, ARTHUR JOSEPH LA FAY, a resident of the city of Toronto, in the county of York, Province of Ontario, 5 Canada, have invented certain new and useful Improvements in Heating Apparatus, of which the following is a specification.

This invention relates to means for increasing the efficiency of the well known hot 10 water and steam heating devices commonly employed in the heating of buildings. The general principle involved in the construction of the apparatus is to utilize the outer surface of the heater as a heating surface 15 over which the hot products of combustion are passed before being led to the smoke stack or chimney. Over this heating surface the hot products of combustion may be led in a zigzag course by means of longitudinal baffles which divide the space between 20 the heater and an outer casing into longitudinal flues, dampers being provided to permit of direct draft whenever desired.

The apparatus is constructed in detail as 25 hereinafter more specifically described and as illustrated in the accompanying drawings in which—

Figure 1 is a front elevation, partly in 30 section, showing a rectangular heater provided with my improvements;

Fig. 2 a side elevation of the same, partly in section; and

Fig. 3 a perspective view with the casing indicated in dotted lines.

35 In the drawings like numerals of reference indicate corresponding parts in the different figures.

1 is a heater of ordinary construction, of 40 which 2 is a smoke collar. The heater is surrounded by a casing 3 of metal or refractory material, which is made completely 45 airtight. Preferably the arrangement of the casing is such that the front of the boiler with its door is exposed, as shown particularly in Fig. 1. The casing, however, is spaced from the rear end of the heater as shown more particularly in Figs. 2 and 3.

The space between the heater and the casing 50 is divided into a plurality of longitudinal communicating flues by means of a plurality of baffles 4. Preferably two baffles are used at each side and two along the top of the heater. A depending flue 5 with which the smoke collar 2 communicates leads 55 to the space at the end of the heater below.

the lower baffles, and in communication with the flue spaces beneath the lower baffles. Openings 6 are provided in the baffles adjacent their ends. Certain of these openings are controllable by means of the sliding 60 dampers 7, 8, 9 and 10. The flue spaces beneath the lower baffles are preferably divided by means of the partition 11, which serves to divide the products of combustion 65 equally between the two sides of the casing. The flue space at the top of the heater is also preferably divided by the longitudinal partition 12, which preferably stops short of the smoke outlet 13 which leads from the rear end of the top flue. 70

Clean-out doors 14 are provided in the front of the casing through which the various flues may be cleaned. When a fire is being started or when it is necessary to establish an extra good draft, the dampers 75 8 are closed and the dampers 7, 9 and 10 opened. The products of combustion then pass down the flue 5, thence laterally and upwardly through the openings controlled by the dampers 7, 9 and 10 to the smoke 80 outlet. When full advantage is to be taken of the external heating surface of the heater, the dampers 7 and 10 are closed. The products of combustion must then take a zig-zag course along each side and top of the 85 heater. If the draft is not sufficiently active to permit of this, the dampers 7 may be opened and the dampers 8 closed. The lowermost flues at each side are then cut out of the circuit and the total travel of the 90 products of combustion reduced.

I find that with the construction shown I am enabled to secure greatly increased efficiency in the operation of a heater while maintaining under all circumstances an adequate draft. 95

I find that there are certain advantages in introducing heated air into the products of combustion near their place of egress from the heater, and I therefore provide the 100 pipe 15 which is led into the lower flue near the front and is carried to the back, where it is provided with a perforated nozzle, whereby the air is thus heated before being mixed in a fine spray with the products of 105 combustion.

What I claim as my invention is:—

1. The combination with a fluid heating furnace of the horizontal type, having a smoke exit at one end of an external casing 110

surrounding the sides and top of the furnace and spaced therefrom, but leaving the front of the furnace casing with the ashpit and fuel doors exposed; longitudinal baffle plates dividing the space between the sides of the casing of the furnace and the external casing into a plurality of longitudinal communicating flues at each side; a depending flue, with which the smoke exit communicates, communicating with the lowermost flue at each side; a smoke outlet leading from the uppermost flue; and dampers whereby the products of combustion may be allowed to pass either substantially directly to the smoke outlet or caused to pass in zigzag fashion through two or more flues at each side of the furnace to the smoke outlet.

2. The combination with a fluid heating furnace of the horizontal type having a smoke exit at one end of an external casing spaced therefrom at the sides, top and smoke outlet end; longitudinal baffle plates dividing the space between the sides and top of the furnace and the external casing into a plurality of communicating flues; a depending flue with which the smoke collar communicates extending down to the level of the lower baffle plates; a smoke outlet leading from the uppermost flue; and dampers whereby the products of combustion may be allowed to pass either substantially directly to the smoke outlet or caused to pass in zigzag fashion through two or more flues at each side of the furnace to the smoke outlet.

3. The combination with a fluid heating furnace of the horizontal type having a smoke exit at one end of an external casing spaced therefrom at the sides, top and smoke outlet end; longitudinal baffle plates dividing the space between the sides and top of the furnace and the external casing into a plurality of communicating flues; a depending flue with which the smoke collar communicates extending down to the level of the lower baffle plates; a smoke outlet leading from the uppermost flue; and dampers whereby the products of combustion may be allowed to pass either substantially directly to the smoke outlet or caused to pass in zig-

zag fashion through two or more flues at 50 each side of the furnace to the smoke outlet; a partition extending from the end of the furnace to the end of the external casing, below the depending flue, dividing the lowermost flues from one another, and a partition 55 extending along the top of the furnace dividing the uppermost flue.

4. The combination with a fluid heating furnace of the horizontal type having a smoke exit at one end of an external casing 60 surrounding the sides and top of the furnace and spaced therefrom; longitudinal baffle plates dividing the space between the sides of the furnace and the external casing into a plurality of longitudinal communicating 65 flues at each side; a flue, with which the smoke collar communicates, communicating with a distant flue at each side; a smoke outlet leading from another flue; and dampers whereby the products of combustion may be 70 allowed to pass either substantially directly to the smoke outlet or caused to pass in zigzag fashion through two or more flues to the smoke outlet.

5. The combination with a fluid heating 75 furnace of the horizontal vertical section type provided with internal flues for the products of combustion and spaces for the fluid to be heated externally bounded by the casing of the furnace and surrounding the 80 external flues, fuel and ashpit doors at one end and a smoke exit at the other end, of an external casing spaced from the sides and top of the furnace casing but leaving the front of the furnace casing with the ashpit and fuel doors exposed; a smoke outlet from 85 said casing; longitudinal baffles at each side of the furnace dividing the space between the casings into substantially horizontal flues; and means for allowing the products 90 of combustion from the furnace smoke exit to either circulate through said flues along the sides and top of the furnace before passing to the smoke outlet of the casing or to pass substantially directly to said outlet.

Signed at Toronto, Canada, this 13th day of March, 1919.

ARTHUR J. LA FAY.
